UNITED STATES PATENT OFFICE.

CARL E. LINCOLN, OF GLENCOE, ILLINOIS, ASSIGNOR, BY MESNE ASSIGNMENTS, TO
GEO. W. WHEELWRIGHT PAPER COMPANY, OF LEOMINSTER, MASSACHUSETTS,
A CORPORATION OF MASSACHUSETTS.

IMPRINTING.

Application filed October 15, 1927. Serial No. 226,329.

This invention relates to imprinting, by which is to be understood the marking of paper and the like by the pressing of designs or figures therein, such marking being 5 accomplished by the compression of portions of the sheet to a degree greater than other portions. The invention has to do primarily with the preparation of the impression plate or roller.

10 For the imprinting of paper and the like heretofore, it has been the practice to prepare an impression-forming member, either as an impression plate or impression roller with the desired design, by engraving, etching, 15 or electroplating. Such methods require considerable time and skilled workmen, and as a consequence involve considerable expense for the preparation of each impression member. It results, therefore, that 20 considerations of economy limit the available designs, it being economically feasible to furnish impression-decorated paper only in such designs as can be sold in sufficiently large quantities to absorb the cost of the 25 preparation of the impression member.

The present invention has for its general object the provision of a novel kind of an impression member and a method of forming same, whereby the cost of such articles, 30 and consequently the cost of impression-decorated paper, may be reduced to a point which renders it economically feasible to furnish distinctive designs in small runs.

Another object is the provision of an improved impression member and a method of forming it, whereby the time required for the production of such an article, and consequently for the production of the impression-decorated paper, may be very substantially reduced from that required with 40 methods now in use.

A further object is the elimination of the necessity for employment of particularly skilled artisans in the making of such impression members.

Another object is the provision of an improved impression member and the method

of forming same which are applicable for use, not only in the imprinting of finished paper and the like, but also to the imprinting 50 of the paper incident to its manufacture.

Another object is the provision of an improved impression member and method of forming same, whereby an infinite number of different designs may be imprinted from 55 a given roller or plate, thus eliminating the necessity for a separate roller or place for each design.

A further object is the provision of an improved impression member and method of 60 forming same whereby a given pattern or design may be applied to an impression plate or roller and subsequently removed with ease, to allow for the further application of a different imprinting pattern 65 thereto.

Other and further objects of the invention will be pointed out or indicated herein-after, or will appear to one skilled in the art upon an understanding of the invention 70 or its employment in practice.

In the drawing forming a part of this specification, I illustrate, largely in diagrammatic fashion, various articles and operations serving to facilitate a disclosure of the 75 invention, but it is to be understood that these are presented entirely for such purpose and are not to be construed in any fashion calculated to limit the appended claims short of the true and most comprehensive scope of the invention in the art.

In said drawing

Fig. 1 is a diagrammatic detail in the nature of a section through an imprinting apparatus, the section being taken perpendicularly to the impression surface.

Fig. 2 is a surface view of an impression member bearing a pattern containing a definite design applied by means of a stencil.

Fig. 3 is a surface view of a portion of an impression member bearing a random design, applied in another fashion, and

Fig. 4 is a perspective view of an impression member in the form of a roller, together

er with a stencil and an air brush for applying the design to the roller in the form of a raised imprinting surface, the illustration being schematic.

5 In the preparation of an impression member, it is necessary to provide an imprinting surface wherein the pattern to be impressed in the paper is formed by portions of different heights, in the nature of embossments or 10 depressions. In the imprinting operation, the paper or the like is subjected to pressure while in contact with the imprinting surface, so that the design is formed in the paper by the impressions of the relatively 15 higher or embossed portions of the imprinting surface. This may have the effect of changing the transparency or translucency of the parts which are thus increased in density, or, in the case of colored paper, may 20 increase the color intensity of the compressed portions. Such changes in appearance are accomplished by a depression of the surface portion subjected to the pressure of the outstanding portions of the imprinting surface. 25 The raised portions of the impression surface must offer a sufficient difference of height from the intervening depressions to render the pattern distinct, and they must also possess such rigidity as to prevent their 30 being deformed under the heavy pressure employed and such durability as to preclude their rapidly being worn down. The present invention provides an impression member 35 having these necessary characteristics, and also a method whereby impression surfaces of an infinite number of designs may be formed, very quickly and very economically, the raised imprint-forming portions of the impression surface being formed by 40 the application to a suitable foundation member, such as a plate or roller, of adhesive material in the form of a solution which will dry or set in place and retain a raised 45 form delineating the pattern. It is desirable also that the applied material be soluble in a liquid which does not affect the foundation member, so that the pattern may be removed from the foundation member 50 when it has served its purpose, and another pattern applied. Thus, a single impression roller may be made to serve for an infinite 55 number of different designs. The material may be applied to the foundation member in any fashion which will admit of a sufficient 60 amount of it adhering to the member to give the raised portions of the impression surface sufficient height. Various lacquers and 65 varnishes may be employed as the impression surface-forming material, it being necessary, however, that they possess the characteristics of setting or drying with sufficient rapidity to hold the embossed or raised 70 form of the pattern elements, and that when 75 set or dried they possess the requisite hardness and strength under compression and the necessary adhesive quality to prevent their scaling off of the foundation member. 80 Among the appropriate materials are the nitrocellulose lacquers of the type known generally under the trade name "Duco." An imprinting surface having a pattern design may be formed very easily by the application of such material through a stencil. For such purposes, stencils may be formed 85 by cutting the pattern in metal sheets or in sheets of heavy paper, or lace of suitable texture may be employed as a stencil. After removal of the stencil from the foundation member, the applied material adhering to the latter is permitted to harden completely, whereupon the impression member is in condition for use. For random designs, the material may be applied to the foundation member without the use of the stencil, the only requisite being that it be distributed in such fashion as to form the raised or up-standing elements of sufficient height to imprint the paper. Moreover, the impression surface may be formed by the use of a material such as that known as crackle varnish. 90 This is a form of lacquer or varnish which has the characteristic of shrinking as it dries, so that its surface portion separates or subdivides into numerous irregularly-shaped island-like spots which stand somewhat elevated above the intervening areas, thus affording impression elements of random form 95 adapted to imprint the paper.

In the drawing are illustrated various examples. In Fig. 4 the reference numeral 10 designates a foundation member in the form of a roller which is adapted for cooperation with another roller to feed the paper therebetween under compression. Here is illustrated 105 the application of the impression surface-forming material to the roller, a stencil 11 being arranged on the surface of the roller and the lacquer solution being applied to the surface of the roller through the stencil 110 by means of a suitable brush, here illustrated as an air brush 12. Fig. 2 illustrates a portion 115 of an impression surface so formed, bearing a lace design, a piece of lace having been used as a stencil. Here the raised elements of the impression surface are shown white, the shaded portions of the pattern representing the depressed parts of the surface pattern.

Fig. 3 illustrates a portion of an impression surface of a random design, such as produced by an application of crackle varnish to the foundation member. Here the areas shown white are the raised portions which constitute the imprinting elements of the 125 surface, while the shaded areas represent the intervening depressions.

The impression surface having been prepared as above described, the applied solution having been allowed to harden to the 130

degree necessary to qualify it to resist the pressures necessary for imprinting the paper, it is arranged in the proper operative association with a coacting pressure member, and the paper or other material to be imprinted is subjected to heavy compression upon the imprinting surface. The raised imprinting elements of the impression surface are thus forced into the paper and caused to 10 compress or increase the density of corresponding areas of the paper, the opposite side of the paper being supported by the coacting pressure member. The operation is illustrated in Fig. 1, wherein the foundation 15 member is illustrated in the form of a plate 14 bearing the upraised imprinting elements 15. The impression member is supported on the press bed 16 for cooperation with a movable pressure-applying member 17. A sheet 20 of paper 18 is subjected to compression upon the impression member by the pressure member 17, and imprinted with the design of the former.

When the imprinting design has become 25 worn down by use, or has served its purpose, it may be removed from the foundation member by the use of a suitable solvent which will soften or dissolve the applied material without affecting the foundation member. After such removal of the applied material, another impression surface may be 30 formed on the foundation member as above described. This feature of the invention is of particular value in connection with roller presses as it precludes the necessity for having a separate roller for each pattern. Inasmuch as the rollers are necessarily quite expensive, the invention thus effects a very 35 substantial saving in expense. In addition to the savings accomplished in this particular, it also effects great saving in the preparation of any impression member, both because of the comparatively short time required for the forming of the impression 40 surface, and the simplicity of the operations involved, which do not require the services of expert artisans such as engravers, etchers or designers. Hence, due to the comparatively small cost involved in the preparation 45 of the impression member, original or distinctive designs or patterns may be furnished for comparatively small lots or runs of paper without rendering the cost prohibitive. Thus, for example, distinctive imprinted 50 designs may be furnished to individuals at small expense for such small orders as Christmas greeting cards and the like, the imprinting surfaces being formed, as above described, on the individual's copper plate 55 from which the cards are printed.

The invention is also susceptible of use in connection with the manufacture of paper, as impression surfaces of the sort described may be applied by the method above ex-

plained to the calendar rollers of paper-making machines, the paper thus being imprinted as the web passes through the calender rollers from the machine. Likewise, the invention may be employed on the dandy rollers of paper-making machines, a selected 65 pattern being applied thereto as above described for forming a water-mark in the paper incident to its manufacture. In such uses, as in imprinting with roller presses, the ease with which the impression surfaces 70 may be prepared, as well as the facility with which they may be removed, are of particular advantage, especially in the direction of allowing unlimited variety of patterns without involving prohibitive cost. 75

What I claim is:

1. The method of forming an impression device for imprinting paper and the like, which comprises applying directly to the surface of an incompressible foundation 80 member an adhesive viscous solution having the capacity for hardening in coherent solid form, and permitting the applied solution to harden on the foundation member with an irregular surface contour above the surface of the foundation member. 85

2. A method of forming an impression device for imprinting paper and the like, consisting in applying directly to interspaced areas of the surface of an incompressible foundation member an adhesive viscous solution having the capacity for hardening in coherent solid form, and permitting the applied solution to solidify on the foundation member to form therewith an unyielding irregular-surfaced imprinting die. 90

3. The method of forming an impression device for imprinting paper and the like which consists in applying an adhesive viscous lacquer directly to limited areas of the 95 surface of an incompressible foundation member, and drying the lacquer to hardness in the form of upstanding elements which form with the foundation member a rigid irregular-surfaced imprinting die. 100

4. The method of forming an impression device for imprinting paper and the like which consists in stenciling with a viscous lacquer a design directly on the surface of an incompressible foundation member, removing the stencil, and permitting the lacquer to dry to hardness as upstanding impression elements on the surface of the foundation member. 105

5. An impression device for imprinting paper and the like, comprising an incompressible foundation member having rigid upstanding imprinting elements adhering directly to its surface, said imprinting elements being soluble in a solvent which is inert to the foundation member. 110

6. An impression device for imprinting paper and the like, comprising a metallic

foundation member with upstanding imprinting elements formed of solidified lacquer adhering directly to its surface.

7. A method of imprinting paper which comprises applying an adhesive viscous solution directly to the surface of an incompressible foundation member, permitting the applied solution to harden on the foundation

member as rigid upstanding impression elements, and subjecting the paper to heavy 10 compression against said elements and foundation member, whereby to vary its density in different areas.

In testimony whereof I have hereunto subscribed my name.

CARL E. LINCOLN.
